SHUTTLE DRIVING MECHANISM FOR LOOMS

Worth Wade, Rosemont, Pa., assignor to American Viscose Corporation, Philadelphia, Pa., a corporation of Delaware

Application November 3, 1951, Serial No. 254,720

16 Claims. (Cl. 139—142)

1

This invention is concerned with a novel and improved system for driving or throwing the shuttle back and forth across a loom.

It is an object of the present invention to make use of an explosive material to provide the propelling force for throwing the shuttle back and forth over the lay or lathe of a weaving loom. The use of such a prime mover for the shuttle has the advantages that the speed of travel of the shuttle through the shed may be increased and the width of the fabric being woven on the loom may be increased over the speeds and widths normally obtainable when using mechanical driving forces for the shuttle. Other objects and advantages of the invention will be apparent from the drawing and the description thereof herein-after.

In the drawing, which is illustrative of the invention,

Figure 1 is a front view of a portion of the right end of the loom showing the shuttle driving system,

Figure 2 is a plan view of the system shown in Figure 1,

Figure 3 shows a modification,

Figure 4 shows another modification,

Figure 5 is a section on line V—V of Figure 1, and

Figure 6 is an end view of a shuttle.

Figure 1 shows the lay or lathe 3 of a loom. This lay extends across the loom and provides the raceway for the shuttle 4. The invention is applicable to looms having an independent lay for beating up the fabric as well as to the most common type in which the lay is swung forward to beat up the fabric. The lay and/or the shuttle raceway extends beneath the warp in front of suitable harness comprising heddles for reversing alternate threads in the warp.

At each end of the lay 3, there is disposed above the lay a shuttle-receiving device or means comprising a chamber 5, a lateral surface of which may be resiliently mounted so as to be urged toward the opposite surface or wall of the chamber to act as a shuttle check. In the embodiment shown, the back wall 6 may be resiliently urged by a spring 7. A pair of arcuate shoes 8 may be disposed in the end of the shuttle-receiving chamber. They are mounted pivotally at 9 on a block 10 and are urged toward each other by means of springs 11. These shoes serve as final limiting bumpers as will be explained hereinbelow.

The block 10 is provided with two longitudinal passages or slots 12 and 13 which extend from the right end of the block as viewed in Fig. 1 clear

10 to the left end of the block. A vertical passage 14 passes through the block and is symmetrically disposed with respect to the slots 12 and 13 but is narrower at the portion adjacent and between the slots as indicated in Fig. 5. A passage 15 interconnects the slots 12 and 13 and extends from the passage 14 to the left end of the block as viewed in Fig. 1. This passage 15 constitutes the firing chamber and is less in width than the slots 12 and 13 but preferably the same width as the portion of passage 14 extending between slots 12 and 13.

As shown in Figs. 1, 2 and 5, the nose of the shuttle has a section which is complementary to the discharge opening of the firing chamber 15 in the left end of block 10. This comprises a central rectangular or square portion 15a which is joined to an upper flat strip 12a and a lower strip 13a. The upper and lower strips 12a and 13a project endwise of the shuttle beyond the intermediate portion 15a as indicated in Fig. 1 so that strips 12a and 13a can pass through the slots 12 and 13 beyond the passage 14 before the front end 15a reaches the passage 14. The frontal edges of the strips 12a and 13a may be rounded at their edges to facilitate their guidance into the slots 12 and 13 at the end of the shuttle travel.

Means is provided for feeding successive charges of explosive one at a time into the passage 14 and in alignment with chamber 15 where it is adapted to be hit by the face 15a of the nose of the shuttle. The face 15a and the back wall 16a of the passage 14 which is in alignment with the passage 15 may be provided with one or more sharp projections 16. A casing 17 has an axle 18 upon which there is supported a wound package of a tape 19 comprising regularly spaced explosive charges 20 thereon, each of which may comprise a main body 20a of dynamite or nitro-cellulose grains, preferably of the smokeless and/or flashless powder type and a small body 20b of a percussion primer of a composition such as is commonly used in the cartridges of guns or rifles. The casing 17 may be supported on the lay by means of a suitable arm or bracket. The tape 19 extends into the nip between a pair of feeding cylinders 21 mounted on shafts 22 by which they are driven in the direction of the arrows. The peripheries of the cylinders 21 may be recessed at intervals as at 23 to provide mating pockets into which an explosive charge may be received. This enables feeding of the tape without exertion of undue pressure on the explosive charges.

The shafts 22 have keyed thereon a pair of

2

intermeshing gears 24 and one of the shafts has keyed thereon a sprocket 25 driven by a chain 26 which is in turn driven by a sprocket 27 fixedly secured to the output element of a one-way clutch 28 which is mounted on the shaft 29 to which a gear 30 is keyed. The gear 30 meshes with the rack teeth 31 of a rack bar 32 which is slidably supported in a guideway 33 of a stationary element 34 which may be secured to the lay 3. A spring 35 is secured to a lug 36 on the rack bar 32 and to a stationary point such as on the member 34 for the purpose of urging the rack bar toward the left as viewed in Fig. 1 in which position it extends through the slot 12 to a position in the block 10 well beyond the passage 14. However, as shown in Fig. 5 especially, rack bar 32 is displaced aside of slot 12 so that it is out of alignment with slot 14 and offset from chamber 15. The one-way clutch permits the gear 30 to be rotated both ways by the rack 31 but transmits the motion of the gear 30 to the sprocket 27 only when the gear 30 is rotating in a clockwise direction as viewed in Fig. 1. Any of the conventional one-way clutches may be used for this purpose.

In operation of the embodiment of Fig. 1, the shuttle is thrown back and forth from one side of the loom to the other by the explosive charges set off on each side thereof. The shuttle, as shown in Figs. 1 and 2, is in a position where it has almost reached the end of its travel to the right. At the position shown, it is being slowed down by the shuttle check. As it proceeds to the right, the strips 12a and 13a cut off the tape 19 on each side of the charge 20. As the shuttle proceeds, the upper strip 12a pushes the rack bar 32 to the right but, as explained hereinabove, the motion in this direction merely turns gear 30 without turning the sprocket 27 because of the one-way clutch 28. Finally, the face 15a of the shuttle strikes the explosive charge and causes its explosion. It should be noted that at this time, the charge 20 is confined within a closed chamber since the slots 12 and 13 are closed by the strips 12a and 13a and the face 15a of the shuttle closes the passage 15. The projections 16 assist in detonating the charge.

The shoes 8 are disposed so that the shoulders of the shuttle bear against them and press them against the springs 11 just before the face 15a strikes the explosive charge. They are so disposed that they do not absorb the forward motion of the shuttle to such an extent as to prevent the impact of the shuttle from exploding the charge. As pointed out hereinabove, the charge is preferably of the smokeless variety and it is also desirable that it be of the flashless variety. A muffler or silencer may be provided at each end of the loom and if a charge is used which is not of the smokeless variety, an exhaust hood or suction duct may be provided in the vicinity of the block 10 to withdraw the fumes below.

As the shuttle is thrown to the left by the explosive charge, the spring 35 returns the rack bar 32 and the teeth 31 rotate the gear 30 and this motion is transmitted by the one-way clutch 28 to the sprocket 27 which drives the chain 26 and in turn the sprocket 25 for driving the gears 24 and the charge feeding cylinders 21. The number of teeth on the rack 32 is correlated to the size of the gear 30 and the sprockets 27 and 25 so as to rotate the cylinders 21 a distance which serves to feed the next charge into the passage 14 in alignment with the chamber 15. The entrance of the passage 14 and its bottom

exit is preferably made wide so that the tape carrying the explosive charges will descend by gravity without interference between the charges thereon and the walls of the block 10. Both the entrance and exits of the passage 14 at the top and bottom respectively are preferably made large to rapidly dissipate the gas developed by the explosion and released when strips 12a and 13a pass to the left beyond the passage 14. While the strips 12a and 13a may project beyond the face 15a the same distance, it may be desirable to have the strip 13a considerably shorter as shown so that the lower end of the passage 14 is exposed before the upper end as the shuttle is thrown to the left as viewed in Fig. 1 so that the gas pressure is largely relieved before the upper strip 12a exposes the entrance of the passage 14. This reduces the upward blast of gas through the entrance 14 sufficiently so that the tape of charges is not greatly disturbed or blown out of the entrance 14. It should be noted that the rack teeth 31 do not begin to engage gear 30 when the rack bar 32 is travelling to the left until strip 12a has opened the entrance of passage 14 to the explosive chamber.

Fig. 3 shows a modification in which a firing pin 40 is provided for striking the explosive charge approximately when the face 15a of the shuttle has reached the end of its travel. In this embodiment, the strip 13a is provided with an extension 13b which engages a reciprocable rod 41 disposed in the slot 13 at the right end thereof as viewed in Fig. 2. The rod 41 is pivotally connected to a lever 42 which is pivotally mounted on a fixed member at 43 and is urged in a counterclockwise direction by a spring 44. The upper end of the lever 42 carries a pawl 45 adapted to engage the teeth 46 of a ratchet 47 which is keyed to a shaft 48. A check-pawl 49 pivotally mounted at 50 is urged by a spring 51 to engage behind the teeth 46 of the ratchet 47 so as to prevent return motion of the ratchet. Another ratchet 52 is keyed to the shaft 48. Ratchet 52 has teeth 53 spaced at intervals around its periphery which are adapted to engage a lug 54 secured to the pin 40. The pin 40 carries a collar 55 fixedly secured thereon and a spring 56 bears against a ring or washer 57 secured in the recess 58 and against the collar 55 so as to normally urge the pin 40 to the left to the position shown. When the shuttle approaches the explosive charge, the projection 13b pushes the rod 41 which rotates the ratchet 47 a quarter of a revolution, thereby rotating ratchet 52 a corresponding amount. Because of rotation of ratchet 52, a tooth 53 thereof pushes the lug 54 on pin 40 to the right. After such pin is retracted, the tooth 53 passes beneath the lug 54 and releases it whereupon the spring 56 urges the pin 40 into the firing position. Preferably, the projection 13b is disposed to one side of the slot 13 so that it is offset from the passage 14 and below the rack rod 32 (see Fig. 5).

In the embodiment of Fig. 3, the shuttle not only serves to feed the next charge after a given explosive charge throws it to the left, but, as it proceeds to the end of its throw and before the explosive charge is set off, it actuates mechanism for striking the explosive charge with a firing pin substantially at the end of the stroke of the shuttle.

Fig. 4 shows an embodiment wherein the shuttle 4a is of standard type and it cooperates with a reciprocable catapult or carriage 60, the rear end of which may be provided with a recess 61 which is complementary to the end 4b of the

shuttle. The forward end of the catapult 60 is provided with a nose 62 shaped like the nose of the shuttle 4 in the embodiments of Figs. 1 to 3. The catapult or carriage 60 may be slidably mounted on the floor 65 of its raceway at the end of the lay of the loom or it may be provided with wheels 63. One or more bumpers 64 provided with springs 66 may be provided for absorbing the impact of the carriage 60 when, after an explosion, it approaches the end of the catapult race 65. The firing structure and explosive feeding structure in this embodiment may be identical to that of Fig. 1 or to that of Fig. 2.

As pointed out hereinabove, the present invention provides for the speeding up of the shuttle motion by utilizing an explosive charge. This has the advantages of making it possible to use wider looms and also to increase the speed of operation of looms.

It is to be understood that changes and variations may be made without departing from the spirit and scope of the invention as defined in the appended claims.

I claim:

1. A system for driving a shuttle in a path across the width of a loom comprising a shuttle; a supply of explosive charges; means for successively positioning the charges adjacent one extremity of the shuttle path; means for firing one of the charges as the shuttle approaches the one extremity of its path; and means for directing the explosive force of the charge so as to drive the shuttle across the loom.

2. A system for driving a shuttle in a path across the width of a loom comprising a shuttle; a supply of explosive charges; means for successively positioning the charges adjacent one extremity of the shuttle path; means for firing one of the charges as the shuttle approaches the one extremity of its path; and means for transmitting the explosive force of the charge to the shuttle to drive it to the other side of the loom.

3. A system in accordance with claim 1 in which the charge positioning means comprises means actuated by the motion of the shuttle as it approaches the said extremity of its path.

4. A system in accordance with claim 1 in which the firing means comprises a movable firing element actuated by the motion of the shuttle as it approaches the said extremity of its path.

5. A system in accordance with claim 1 in which the firing means comprises a firing pin which is actuated by the motion of the shuttle as it approaches the said extremity of its path.

6. A system for driving a shuttle in a path across the width of a loom comprising a shuttle; a firing chamber having an opening which is arranged to receive the shuttle as it approaches one extremity of its path; a supply of explosive charges; means for successively positioning the charges in the chamber; means for firing one of the charges by percussion as the shuttle approaches the one extremity of its path; and means for directing the explosive force of the charge so as to drive the shuttle across the loom to the other extremity of its path.

7. A system in accordance with claim 6 in which the charge-positioning means comprises means actuated by the motion of the shuttle as it approaches the one extremity of its path.

8. A system in accordance with claim 6 in which the firing means comprises a firing pin

actuated by the motion of the shuttle as it approaches the one extremity of its path.

9. A system for driving a shuttle in a path across the width of a loom comprising a shuttle; a firing block having an opening and a chamber formed therein and arranged to receive the shuttle as it approaches one extremity of its path, said block also having a pair of passages which extend substantially parallel to the opening through the entire length of the block; a supply of explosive charges; means including a passage transverse to the length of the block communicating with the chamber for successively positioning the charges therein; and means for firing one of the charges by percussion as the shuttle approaches the one extremity of its path, the leading extremity of the shuttle having a pair of elongated projections which extend outwardly and longitudinally therefrom and which are arranged to slidably cooperate with the said pair of passages in the block to close off the said transverse passages during the actuation of the firing means.

10. A system for driving a shuttle in a path across the width of a loom comprising a shuttle; a firing block having an opening and a chamber formed therein and arranged to receive the shuttle as it approaches one extremity of its path, said block also having a passage which extends along one side of the opening and the chamber through the entire length of the block; a supply of explosive charges; a reciprocable member positioned in said passage; means connected to the reciprocable member for successively positioning the charges in the firing chamber; and an element projecting from the leading end of the shuttle for slidably engaging the said passage and actuating the reciprocable member.

11. A system for driving a shuttle in a path across the width of a loom comprising a shuttle; a firing block having an opening and a chamber formed therein and arranged to receive the shuttle as it approaches one extremity of its path, said block also having a passage which extends along one side of the opening and the chamber through the entire length of the block; a supply of explosive charges; means for successively positioning the charges in the chamber; a reciprocable member positioned in the said passage; a firing pin movable into and out of the chamber; means connected to the reciprocable member for actuating the firing pin; and an element projecting from the leading end of the shuttle for slidably engaging the said passage and actuating the reciprocable member.

12. A system for driving a shuttle in a path across the width of a loom comprising a shuttle; a firing block having an opening and a chamber formed therein and arranged to receive the shuttle as it approaches one extremity of its path, said block also having a pair of passages which extend along opposite sides of the opening and the chamber through the entire length of the block; a supply of explosive charges; means including a passage transverse to the length of the block communicating with the chamber for successively positioning the charges therein; a reciprocable member positioned in one of the said pair of passages; means engaged by said member for actuating the charge positioning means; a firing pin movable into and out of the chamber; a second reciprocable member positioned in the other of said pair of passages; means connected to the said second reciprocable member for actuating the firing pin and a pair of elements pro-

jecting outwardly and longitudinally from the leading end of the shuttle which slidably engage the said pair of passages and contact the said reciprocable members positioned therein.

13. A system for driving a shuttle in a path across the width of a loom comprising a shuttle; a raceway positioned adjacent one extremity of the path; a reciprocable carriage which is positioned on the raceway, one extremity of the carriage being arranged to receive the leading edge of the shuttle as it approaches the said extremity of its path; a firing block having an opening and a chamber formed therein and arranged to receive the opposite extremity of the carriage; a supply of explosive charges; means for successively positioning the charges in the chamber; means for firing one of the charges by percussion when the shuttle engages the one extremity of the carriage and approaches the said extremity of its path; and means for directing the explosive force of the charge so as to drive the shuttle across the loom.

14. A system for driving a shuttle in a path across the width of a loom comprising a shuttle; a raceway positioned adjacent one extremity of the path; a reciprocable carriage which is positioned on the raceway, one extremity of the carriage being arranged to receive the leading extremity of the shuttle as it approaches the said extremity of its path; a firing block having an opening and a chamber formed therein and arranged to receive the opposite extremity of the carriage, said block also having a passage which extends along one side of the opening and the chamber through the entire length of the block; a reciprocable member positioned in the said passage; a supply of explosive charges; means connected to the reciprocable member for successively positioning the charges in the chamber; and an element projecting outwardly and longitudinally from the leading end of the carriage for engaging the reciprocable member as the shuttle approaches the said extremity of its path.

15. A system for driving a shuttle in a path across the width of a loom comprising a shuttle; a raceway positioned adjacent one extremity of the path; a reciprocable carriage which is posi-

tioned on the raceway, one extremity of the carriage being arranged to receive the leading end of the shuttle as it approaches the said extremity of its path; a firing block having an opening and a chamber formed therein and arranged to receive the opposite extremity of the carriage, said block also having a passage which extends along one side of the opening and the chamber through the entire length of the block; a supply of explosive charges; means for successively positioning the charges in the chamber; a reciprocable member positioned in the said passage; a firing pin movable into and out of the chamber; means connected to the reciprocable member for actuating the firing pin; and an element projecting from the leading end of the carriage which slidably engages the said passage and actuates the reciprocable member.

16. A system for driving a shuttle in a path across the width of a loom comprising a shuttle; a raceway positioned adjacent one extremity of the path; a reciprocable carriage which is positioned on the raceway, one extremity of the carriage being arranged to receive the leading end of the shuttle as it approaches the said extremity of its path; a firing block having an opening and a chamber formed therein and arranged to receive the opposite extremity of the carriage, said block also having a pair of passages which extend along opposite sides of the opening and the chamber and through the entire length of the block; a supply of explosive charges; a reciprocable member positioned in one of the said pair of passages; means connected to the said member for feeding one of the explosive charges through a transverse passage in the block into the chamber; a firing pin movable into and out of the chamber; a second reciprocable member positioned in the other of the said pair of passages; means connected to the second reciprocable member for actuating the firing pin; and a pair of elements projecting outwardly and longitudinally from the leading end of the carriage for slidably engaging the said pair of passages and actuating the said reciprocable members.
